UNITED STATES PATENT OFFICE.

REUBEN M. CLARK, OF WEBB CITY, MISSOURI.

ORE-SEPARATOR.

No. 922,259.

Specification of Letters Patent.

Patented May 18, 1909.

Application filed January 25, 1909. Serial No. 474,037.

To all whom it may concern:

Be it known that I, REUBEN M. CLARK, a citizen of the United States, residing at Webb City, Jasper county, Missouri, have 5 invented an Improvement in Ore-Separators, of which the following is a specification.

My invention is an improvement in ore-separators of the type commonly known as jiggers, and in which a vertically oscillating plunger is employed for forcing water up 10 through ore resting upon a sieve or grate.

My invention is embodied in a cheap and simple attachment for jiggers of this class, 15 the same comprising a metal box of the form and construction adapted for insertion and use in a jig box, and having a horizontal top forming the overflow line and a series of horizontal slots, and a slidable gate 20 provided with corresponding slots and a nut and screw for adjusting such gate as required to vary the size of the openings or slots through which the ore is discharged.

The invention further consists in providing such metal box with a removable portion which is provided with the aforesaid slots and with a socket or guideway for the 25 slidable gate.

The details of construction, arrangement, 30 and combination of parts are as hereinafter described, and illustrated in the accompanying drawing in which—

Figure 1 is a vertical transverse section of a portion of an ore-separator of the class 35 before specified, with my improved attachment applied and secured in working position. Fig. 2 is a perspective view of my improved attachment, including a portion of the frame of the separator. Fig. 3 is an 40 enlarged vertical cross section on the line 3—3, Fig. 1. Fig. 4 includes a face view and end view. Fig. 5 is a vertical section on the line 5—5 of Fig. 1. Fig. 6 is a vertical cross section of an ore-separator of the class 45 before specified, provided with my improved attachment.

A indicates the metal ore-discharge box which forms part of my invention, and B the side portions of the frame or box of an 50 ore-separator of the type indicated. As shown in Fig. 6, a vertically oscillating plunger C, operated by an eccentric D, is arranged in a side compartment of the box or separator frame B, and the box A, before 55 referred to, is arranged in the opposite or adjoining compartment. There is nothing

new in the arrangement of these parts so far as described.

The box A has a horizontal top, parallel vertical ends, and an inclined bottom. It is 60 held in place between the parallel portions of the box or frame B by means of slotted vertical cleats 1 (see Figs. 1 and 6), which are arranged on the opposite side of the compartment, the narrow and wider end of 65 the box sliding down into the slots and resting at the bottom thereof. In practice, a wedge is inserted at one end of the box, for holding it more securely in place, but its own gravity is practically sufficient for the 70 purpose. By making its ends parallel and smooth, the box is adapted to be thus inserted, and easily removed, if required. The box is made of such lengths as to be applicable for ore-separators of this class 75 which may be constructed in different dimensions.

The inner side and top portion of the box A are cut away and otherwise constructed to receive a removable ore-discharger and 80 gate-guide E, which is shown in Fig. 4 detached. The same consists of a metal casting having a series of rectangular horizontal slots 2 and a face groove 3, which provides a guideway for the slidable gate F. This gate is provided with slots 2^a similar in form and arrangement to the slots 2 of the guide E. The gate is an elongated metal bar fitted somewhat loosely in the guideway 3 and held 85 therein by means of lugs 4, which are cast on the body of the guide E and project over the groove or guideway 3, as shown in several figures. The gate F works in a slot formed in the left-hand side of the box or frame B, a stuffing-box 5 being provided at 90 that point as shown in Fig. 1, in order to prevent the escape of water from the box. The end of the gate is provided with a screw stem 6, which works in a nut 7 whose reduced portion is held rotatably in a bracket 95 8, that is attached by bolts 9 to the outer side of the box or frame B. A hand-wheel 10 is keyed on the nut 7 for use in rotating it, whereby the gate F may be adjusted in one direction or the other, for the purpose 100 of closing or opening the ore discharge slots 2 of the box A as may be required. The aforesaid bolts 9 pass also through a plate 11 (see Fig. 2) and thus secure the latter to the box B. The lower end of this plate is provided with an opening 12 and a pivoted 105 valve or gate 13 adapted to close the same.

The opening 12 communicates with a corresponding opening at the lower end of box A.

It will be understood that, in practice, a series of compartments is provided and a corresponding series of vertically oscillating plungers C, and that the box or frame B is filled with water up to the height of the ore box A. The ore to be separated is discharged by suitable means upon a grate 14 (see Figs. 1, 5 and 6) and the oscillation of the plunger C forces the water up through it with considerable rapidity. The valuable portion of the ore being the heavier, remains on the bottom of the grate, while the "chats" or "middlings" that is to say, the less valuable portion comprising ore and rock or waste material which adhere to each other, will be forced upward and lie as a stratum 20 on the ore, as shown in Fig. 5. A lighter and waste portion which is utterly valueless forms a third or top stratum and is carried off with the water over the box A.

My invention is designed particularly for use in jiggers employed in the separation of lead and zinc ores which are mined in southwestern Missouri. Ore boxes of this general character are in general provided with rotary valves having a slot extending their entire length or with vertically adjustable valves, both of which are open to objection, chiefly on account of obstruction of pieces of ore beneath them. With a gate or cut-off slideable horizontally, adjustment is never interfered with or prevented and the same vertical depth of the discharge openings remains at all times. The fine particles of the ore fill the slight cracks or spaces around the box proper and the gate F so that it is often extremely difficult to move either when required. Hence, I have found that a lever as a means for adjusting the gate is far inferior to the screw attachment which I have provided and which is perfectly efficient. The passage of the ore through the openings 2 wears that portion of the box more or less and consequently replacement of the box by a new one is sooner or later required. To avoid the expense of replacing the entire box, I have provided it with the removable gate holder and guide E, the same being an elongated rectangular frame-piece having tenons at the ends which enter vertical grooves in the ends of the box proper. Thus

by first removing the gate F, that is to say, by withdrawing it out through the slot in the lefthand side of the ore box B, the frame E may be raised and thus lifted entirely free of the body of the box and a new one of similar construction and size may be inserted 60 in its place.

It will be seen that in order to provide an ore separator or more particularly its box B with my ore discharging box A constructed as before described, it is only necessary to apply cleats 1 or equivalent supports to the opposite sides B of the jigger and to drop the box A into place, the gate F of the same having been first removed. Then, the gate having been reinserted, the bracket 8 and 70 plate 11 are bolted in place and the nut screwed on the gate stem 6 and secured to the bracket by a small nut 15.

What I claim is:

1. The improved attachment for ore-jiggers of the class indicated comprising a metal box having a horizontal top adapted to serve as an overflow line, an inclined bottom and parallel vertical ends, and provided with a horizontal groove forming a guideway for a gate and having slots formed in such groove and whose lower sides are horizontal, the interior of the box being thus closed to influx from the overflow and adapted to maintain discharge at a uniform level; 80 a slideable gate provided with a screw stem, a hand nut applied thereto and a bracket supporting such nut and means for securing the bracket to the frame of the jigger, as shown and described. 90

2. The improved attachment for ore-jiggers of the class indicated comprising a metal box having a horizontal top adapted to serve as an overflow line, an inclined bottom and parallel vertical ends, and provided with a horizontal groove forming a guideway for a gate and having slots formed in such groove and whose lower sides are horizontal, the interior of the box being thus closed to influx from the overflow and adapted to maintain discharge at a uniform level; 85 a slideable gate arranged for closing the slots more or less and means for adjusting said screw, as shown and described. 100
